(57) **CLAIM**

The ornamental design for a battery, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top perspective view of a first embodiment of a battery showing our new ornamental design;

FIG. 2 is a front view thereof;

FIG. 3 is a back view thereof;

FIG. 4 is a top view thereof; and

FIG. 5 is a bottom view thereof.

FIG. 6 is a top perspective view of a second embodiment of a battery showing our new ornamental design;

FIG. 7 is a front view thereof;

FIG. 8 is a back view thereof;

FIG. 9 is a top view thereof; and

FIG. 10 is a bottom view thereof.

FIG. 11 is a top perspective view of a third embodiment of a battery showing our new ornamental design;

FIG. 12 is a front view thereof;

FIG. 13 is a back view thereof;

FIG. 14 is a top view thereof; and,

FIG. 15 is a bottom view thereof.

FIGS. 11 through 15 are colored drawings.

**1 Claim, 9 Drawing Sheets
